US00D688620S

(12) **United States Design Patent**
Burtt

(10) **Patent No.:** **US D688,620 S**
(45) **Date of Patent:** **** Aug. 27, 2013**

(54) **THERMAL SOLAR CELL**

(75) Inventor: **Eric M. Burtt**, Orinda, CA (US)

(73) Assignee: **EchoFirst, Inc.**, Fremont, CA (US)

(**) Term: **14 Years**

(21) Appl. No.: **29/357,428**

(22) Filed: **Mar. 11, 2010**

Related U.S. Application Data

(60) Continuation of application No. 29/342,710, filed on Aug. 31, 2009, now Pat. No. Des. 613,243, which is a division of application No. 29/329,770, filed on Dec. 20, 2008, now Pat. No. Des. 601,491.
